[57] CLAIM

The ornamental design for golf club head, as shown and described.

DESCRIPTION

FIG. 1 is a top, rear and right side perspective view of a golf club head showing my new design;
FIG. 2 is a right side elevation view thereof, the undisclosed opposite side being a mirror image;
FIG. 3 is a front elevation view thereof;
FIG. 4 is a rear elevation view thereof;
FIG. 5 is a top plan view thereof; and,
FIG. 6 is a bottom view thereof.
The broken line showing of shaft on FIG. 1 is for illustrative purposes only and forms no part of the claimed design.
